FLUORESCENT LAMP

Luke Thorington, Berkeley Heights, and Gerald Schiavano, Bloomfield, N.J., and Joel Shurgan, Brooklyn, N.Y., assignors to Duro-Test Corporation, North Bergen, N.J., a corporation of New York

Filed July 25, 1962, Ser. No. 71,066

Term of patent 14 years

(Cl. D26—8)

FIGURE 1 is an exploded side elevational view of a fluorescent lamp broken in two halves for convenience in illustration, which joined shows our new design;

FIGURE 2 is an end elevational view of either end thereof; and

FIGURE 3 is a typical cross-sectional view through the twisted portion of the lamp.

We claim:
The ornamental design for a fluorescent lamp, as shown and described.
